UNITED STATES PATENT OFFICE.

WARREN H. BLAKE, OF LOS ANGELES, CALIFORNIA.

INVALID CARRIER OR BAG.

Application filed October 4, 1926. Serial No. 139,369.

This invention relates to an invalid carrier or bag which is intended to be used by a fireman in effecting the rescue of persons from burning buildings and particularly hospitals.

5 The general object of this invention is to provide a device of this nature which is so constructed that it can be quickly applied as an envelope or bag to carry an invalid with safety. The device is constructed in such a 10 way that it can be handled on a line or rope suspended from above to enable the carrier with the body in it to be lowered to the ground through a window, and then carried as a stretcher.

15 One of the objects of the invention is to provide a device of this kind which is constructed so as to enable it to be applied to bodies of different size; also to provide fastening means which can be quickly put in place 20 when securing the body in the bag.

A further object of the invention is to provide an improved construction for securing a sling to the upper end of the bag.

Further objects of the invention will appear hereinafter.

The invention consists of the novel parts and combination of parts to be described hereinafter, all of which contribute to produce an efficient invalid carrier or bag.

30 A preferred embodiment of the invention is described in the following specification, while the broad scope of the invention is pointed out in the appended claims.

In the drawing:

35 Figure 1 is a front elevation of the bag or carrier and representing the same folded as it should be when a body is being carried within it.

Figure 2 is a view showing the bag lying 40 flat and partially folded.

Figure 3 is a section taken through the upper edge of the bag and particularly illustrating the means for securing the sling to the upper edge of the bag.

45 In practicing my invention, I provide an elongated sheet 1 of substantially rectangular form and this sheet is provided at one side with an integral flap 2 which constitutes the inner flap when the sheet is folded into the bag form. Opposite this flap 2, the sheet is provided with an outer flap 3 which may be considered as having its root or point of connection with the sheet 1 along the dotted line 4.

55 In order to facilitate folding these flaps

over a body to be surrounded by the bag, I provide a plurality of rings 5 which are attached along a line near one edge of the sheet 1 and near the root of the flap 3. On the inner flap 2, opposite these rings, I provide 60 straps 6. These straps are adapted to be passed through the rings 5 so as to form loops to hold the flap 2 close against the body which is to be enveloped. Each strap is provided with a hook 7 and in line with each strap 6, I 65 provide a plurality of rings 8 on the flap 2. These rings are preferably attached to each strap 6 by means of an extension 6^a of each strap which is sewed or otherwise fastened securely to the flap. These rings 8 are different distances from the edge 9 of the inner flap 2 and this enables the tightness of the flap 2 against the body to be adjusted. For example, if the body is that of a child, the hook 7 would be secured to the ring 8 which is 70 furthest to the left as indicated by the dotted lines in Figure 2. After looping all the straps 6 through the rings 5 and attaching their hooks to the proper rings, the outer flap 3 is then folded over the inner flap. On the 75 edge of this flap 3, hooks 10 are provided and these hooks are in line with rings 11 secured on the flap 2 at a distance from the edge 9. I provide means at the lower end of the device 80 to support the feet of the body which is to be carried; this means may be in the form of a flap or tongue 12. After securing the flaps 2 and 3 over the body by attaching the hooks 10 to the rings 11, a flap or tongue 12, which extends down from the lower edge of the sheet 85 1, is then folded up in line with the flaps and preferably on the outer side of the flaps, and this tongue is secured to one of the flaps near the upper edge of the sheet. For this purpose, the tongue 12 may be provided with a strap 13 which may be secured in a buckle 14 (see Figure 1). In this way, the device is 90 folded up into a bag 15 or envelope around the body.

The upper edge 16 of the bag is provided with a sling 17 to enable it to be attached to a hook on a rope. This rope can be arranged in any suitable manner to enable the bag with the body in it to be lowered out of a window. The sling may be constructed in any suitable 100 manner but preferably comprises a D ring 18 from which cords 19 extend downwardly, said cords being doubled and terminating at their lower ends in loops 20 which are passed outwardly through eyes or openings 21 near the 105 110

upper edge of the bag (see Figure 3). These loops 20 are all locked in place by a cord 22 which extends through them and passes along the entire upper edge of the bag.

5 It will be evident that in using this device, the straps 6 may be very quickly passed through the rings 5 and the hooks 7 applied to the proper rings 8 to secure the inner flap in place. Likewise, the hooks 10 enable the 10 outer flap 3 to be very quickly folded over and secured to the rings 11. The strap 13 may be secured without delay in the buckle 14. In this way, the sheet can be very quickly applied to a body and wrapped around it so as 15 to form a bag. The lower portion of the tongue 12 forms the bottom 23 for the bag so as to keep the body in it while it is being lowered from a window.

I prefer to construct the device so that it can 20 be carried like a stretcher in a horizontal position with a body within the sheet. For this purpose, I provide stiffeners along the side edges of the sheet. These stiffeners are in the form of bars 23 and these bars 23 are prefer- 25 ably made in two sections so that there is a gap formed at the point 24 between the sections of the bar which lie on the same side of the device.

Handles are provided for carrying the de- 30 vice, and these handles are preferably formed by leaving a portion 25 of each bar exposed, the remainder of the bar being enveloped in a sleeve 26 of fabric which extends along each side of the device. These sleeves should be 35 placed at the junction of the flaps 2 and 3 with the body of the sheet. By forming the bars 23 in sections as described, they do not interfere with folding up the sheet into a compact package or pack.

40 It will be evident that this invalid carrier or bag enables a body to be enveloped and securely fastened within a sheet to enable it to be carried as a bag when being elevated or lowered by means of the sling 17, and it also 45 enables the device to be used as a stretcher if it is necessary to carry the body in a horizontal position, for example, in placing it in an ambulance.

It is understood that the embodiment of the 50 invention described herein is only one of the many embodiments this invention may take, and I do not wish to be limited in the practice of the invention, nor in the claims, to the particular embodiment set forth.

55 What I claim is:

1. A device of the kind described having a sheet with an inner flap on one side and an outer flap on the opposite side, said flaps constructed to fold over a body to be covered by 60 the sheet, means for securing the inner flap to the sheet adjacent the root of the outer flap, means for securing the outer flap near its edge to the outer side of the inner flap, a tongue carried by the lower end of the sheet so as to 65 fold up in line with the flaps and having

means for securing the same near its upper edge to the outer flap, so as to hold the feet of the body and retain the body's weight on the tongue and a sling secured to the upper end of the sheet opposite the said tongue for supporting the body carried therein. 70

2. A device of the kind described having a sheet with an inner flap on one side and an outer flap on the opposite side, said flaps constructed to fold over a body to be covered by the sheet, a plurality of rings attached to the inner flap at points removed from the edge of the same, a plurality of straps carried by the edge of the inner flap opposite the rings, respectively, a plurality of rings carried by the sheet near the root of the outer flap and adapted to have the said straps passed through the same when the inner flap is folded over a body surrounded by the said sheet, said straps having hooks for securing the ends of the same to the first named rings, means for securing the outer flap near its edge to the outer side of the inner flap, a tongue carried by the lower end of the sheet so as to fold up in line with the flaps and having means for securing the same near its upper edge to one of said flaps, and a sling secured to the upper end of the sheet for supporting a body carried therein. 85 90

3. A device of the kind described having a sheet with an inner flap on one side and an outer flap on the opposite side, said flaps constructed to fold over a body to be covered by the sheet, a plurality of rings attached to one side of the sheet near the root of the outer flap, a strap corresponding to each ring attached to the inner flap and adapted to be passed in a loop through its corresponding ring, said straps having hooks on their ends, respectively, said inner flap having a plurality of rings in line with the said straps to be engaged by the said hooks when the straps have been looped through the first named rings, means for securing the outer flap near its edge to the outer side of the inner flap, a tongue carried by the lower end of the sheet so as to fold up in line with the flaps, and having means for securing the same near its upper edge to one of said flaps, and a sling secured to the upper end of the sheet for supporting a body carried therein. 100 105 110 115

4. A device of the kind described having a sheet with an inner flap on one side and an outer flap on the opposite side, said flaps constructed to fold over a body to be covered by the sheet, a plurality of rings attached substantially in a row on the sheet near the root of the outer flap, a strap corresponding to each ring of the said row attached to the inner flap in line with its corresponding ring, a plurality of rings carried by said straps on the inner flap, each strap having a hook on its end and constructed to be passed through the first named rings, respectively, to form loops securing the inner flap in position, said hooks enabling the ends of the straps to be 120 125 130

- secured to any one of the last named rings, a plurality of hooks carried by the outer flap, rings carried by the inner flap to engage the last named hooks to hold the outer flap folded over the inner flap, a tongue carried by the lower end of the sheet so as to fold up in line with the flaps and having means for securing the same near its upper edge to the outer flap, and a sling secured to the upper end of the sheet for supporting a body carried therein.
5. A device of the kind described having a sheet with an inner flap on one side and an outer flap on the opposite side, said flaps constructed to fold over a body covered by the sheet, a plurality of rings attached substantially in a row on the sheet near the root of the outer flap, a strap corresponding to each ring of the said row attached to the inner flap 20 in line with its corresponding ring, a plurality of rings carried by each strap on the inner flap, each strap having a hook on its end and constructed to be passed through the first named rings, respectively, to form a loop securing the inner flap in position, said hooks enabling the ends of the straps to be secured to any one of the last named rings, a plurality of hooks carried by the outer flap, rings carried by the inner flap to engage the 25 last named hooks to hold the outer flap folded over the inner flap, a tongue carried by the lower end of the sheet so as to fold up in line with the flaps and having means for securing the same near its upper edge to the outer flap, the upper edge of said sheet having a plurality of eyes, a ring with a plurality of cords attached thereto with loops extending through the said eyes, and a locking cord extending through the loops of the cords and 30 passing around the upper edge of the sheet to lock the cords to the same.
6. A device of the kind described having a sheet with an inner flap on one side and an outer flap on the opposite side, said flaps constructed to fold over a body to be covered by the sheet, means for securing the inner flap to the sheet adjacent the root of the outer flap, means for securing the outer flap near its edge to the outer side of the inner flap, a tongue 35 carried by the lower end of the sheet so as to fold up in line with the flaps and having means for securing the same near its upper edge to the outer flap, the upper edge of the sheet having a plurality of eyes, a ring with a plurality of cords attached thereto with loops extending through the said eyes, and a locking cord passing through the said loops and along the edge of the sheet.
7. A device of the kind described having a sheet with oppositely disposed flaps constructed to fold across a body to be conveyed by the sheet, means for securing the flaps, a tongue carried by the lower end of the sheet so as to fold up in line with the flaps and having means for securing the same, a sling secured to the upper end of the sheet for supporting a body carried therein, in a substantially vertical position, and stiffeners carried on opposite sides of the sheet with handles enabling the device to be carried as a stretcher 70 in a horizontal position, when a body is enveloped by the flaps.
8. A device of the kind described having a sheet with oppositely disposed flaps constructed to fold across a body to be conveyed by the sheet, means for securing the flaps, a tongue carried by the lower end of the sheet so as to fold up in line with the flaps and having means for securing the same, a sling secured to the upper end of the sheet for supporting a body carried therein, in a substantially vertical position and stiffeners in the form of bars secured along opposite sides of the sheet near the junction of the body of the sheet with the said flaps, said bars having portions operating as handles to enable the device to be carried as a stretcher in a horizontal position, when a body is enveloped by the flaps.
9. A device of the kind described having a sheet with a sling at one end and having oppositely disposed flaps constructed to fold across a body to be conveyed by the sheet, and means at the other and lower end of the sheet forming a pocket to engage the feet of the body to support the body in the sheet when supported by the sling whereby the body is retained within the folded sheet.

Signed at Los Angeles, California, this 25 day of Sept., 1926.

WARREN H. BLAKE.
